UNITED STATES PATENT OFFICE.

THOMAS R. COOK, OF PITTSBURGH, PENNSYLVANIA.

DESIGN FOR A COVER FOR SECONDARY BATTERIES.

6,651.

Specification for Design.

Patented Nov. 23, 1920.

Application filed August 10, 1920. Serial No. 402,697. Term of patent 14 years.

o all whom it may concern:

Be it known that I, THOMAS R. COOK, a citizen of the United States, residing at Pittsburgh, in the county of Allegheny and state of Pennsylvania, have invented a new, original, and ornamental Design for a Cover for Secondary Batteries, of which the following is a specification, reference being had to the accompanying drawing, forming part hereof.

In the drawing:

Figures 1 and 3 are top and bottom plan

views of the cover, and Fig. 2 is a side plan view thereof.

I claim:

The ornamental design for a cover for secondary batteries, as shown.

THOMAS R. COOK.

Witnesses:

A. HERMAN WEGNER,
E. B. WELSH.
